UNITED STATES PATENT OFFICE.

HAMILTON RICE, OF MYSTIC, CONNECTICUT.

EMBOSSING-MACHINE.

SPECIFICATION forming part of Letters Patent No. 705,297, dated July 22, 1902.

Application filed October 22, 1901. Serial No. 79,574. (No model.)

To all whom it may concern:

Be it known that I, HAMILTON RICE, a citizen of the United States, residing at Mystic, in the county of New London, State of Connecticut, have invented certain new and useful Improvements in Embossing-Machines, of which the following is a full, clear, and exact description.

This invention is in the class of embossing-machines commonly used by bookbinders and printers; and my immediate purpose is to improve the mechanism of such machines, to the end that the greatest power shall be exerted at the instant of the impact of the embossing-dies. This desirable result I attain by means of an extremely simple system of coöperating levers, as explained in detail hereinafter.

To assist in explaining my invention, the accompanying drawings have been provided, which serve to illustrate the same, as follows:

Figure 1 is a front elevation of an embossing-press embodying my newly-invented improvements. Fig. 2 is an elevation of the said press as seen from the right-hand side of Fig. 1. Figs. 3 and 4 illustrate in elevation and partly in section a portion of the mechanism of the said press detached from the machine proper, said figures serving to better illustrate the manner of its operation. Fig. 5 illustrates in plan certain elements of the said mechanism. Fig. 6 embraces two views illustrating the operation of a certain stop-motion provided for the machine.

Referring to the drawings, the letters *a* and *a'* denote the end frames of the machine. Supported by the said end frames *a a'*, at their upper ends, is a cross-head or frame *b*, whose opposite ends are enlarged, as at *b' b''*, and bored for the reception of vertically-extending rods *c c'*, and in order to secure the said rods in place the upper portions thereof are threaded to receive nuts *c²*, as seen in the drawings. The rods *c c'* lie partly within the outer faces of the end frames *a a'*, the said frames being provided with substantially semicircular channels or depressions *a²* for the reception of the said rods *c c'*, and in order to secure the rods *c c'* in the said semicircular depressions caps *a³* are provided at suitable points on the end frames. Secured to the lower ends of the rods *c c'* is a cross-frame *d*, which, like the frame *b*, is enlarged and bored

at its opposite ends for the reception of the lower ends of the said rods. The rods *c c'* are threaded at their lower ends to receive nuts *c²*, which latter serve to bind the cross-frame *d* to the cross-head *b* and also to prevent the separation of the lower ends of the side frames *a a'*. It should now be understood that the rods *c c'*, with the upper cross-bar *b* and the lower cross-bar *d*, form a rectangular framework that is held in its upright position by the end frames *a a'*, but is not rigidly secured to said end frames.

In common with the class of machinery to which this invention relates the newly-invented press is provided with a stationary table or platen on which are mounted suitable dies that are adapted to be engaged by companion dies carried by a traveling table.

The stationary table or platen just mentioned is formed as a part of the cross-frame *b* and is provided by widening the central portion of the said cross-frame, as denoted by the letter *b⁴*. The traveling table or bed-plate is mounted upon a carriage adapted to travel upon the rods *c c'*. The said carriage consists of a frame *e*, having bearings *e' e²* formed thereon for the reception of the said rods *c c'*. The carriage *e* is also provided with suitable ways *e³* on its upper side, in which the bed-plate proper, *e⁴*, is adjustably mounted.

The carriage *e* is adapted to travel with a vertically-reciprocating motion upon the rods *c c'*, and in order to provide very powerful means for actuating the said carriage a peculiar system of "toggle-joint" mechanism and levers is utilized, one member or link of which joint is denoted by the reference-letter *f*, while the companion member or link (which is preferably extensible, as hereinafter described) is denoted by the letters *g* and *g'*. The link *f* is hinged at its lower end to the cross-bar *d* and at its upper end to the extensible link *g g'*, the upper end of the latter section being hinged to the carriage *e*. It will now be seen that when power is applied to straighten toggle *f g g'* the carriage *e* will be caused to travel upward on the rods *c c'*, the highest point in its travel being reached when the alinement of the sections *f g g'* has been accomplished, as shown in Fig. 3, and whenever the members of the toggle are moved out of alinement, as in Fig. 2, the car-

riage will be lowered correspondingly. When the press is in service, the plate b^4 and the table e^4 are provided with dies that are adapted to engage each other to emboss any predetermined design upon paper, brass, or other sheet material placed between them. Describing now the mechanism for actuating the said toggle-joint, the letter h denotes the initial or driving shaft of the machine, which 10 shaft is mounted in suitable bearings in the end frames a a' and bears at one end a driving-wheel k and at its opposite end a spur-gear m . The driving-wheel k is preferably of considerable weight and serves also as a 15 balance-wheel for the machine. Located beneath the shaft h and extending parallel therewith is a shaft h' , having bearings in the frames a a' , and mounted thereon is a gear m' , that meshes with and is driven by the 20 spur-gear m . The gear m' is provided on its side with a crank-pin m^2 , to which is secured one end of the link o , whose opposite end is connected to the crank-pin p' of a crank p . The crank p is mounted upon the projecting end 25 of a rock-shaft s , that extends parallel with the shafts h and h' and, like the said shafts, is hung in bearings in the end frames a a' . The shaft s has formed thereon a pair of slotted arms s' , to the end of each of which is 30 hinged one end of a link s^2 , the opposite ends of said links being hinged to a rod f' , supported in ears f^2 , formed on the link f of the toggle-joint. It will now be seen that when the driving shaft h is set in rotation like motion will be 35 imparted through the gears m m' to the shaft h' and also that through the link o , connecting the crank-pins m^2 and p' , the arm p and its shaft s will be caused to rock in alternating directions in their bearings. The rocking 40 of the shaft s imparts like motion to the arms s' , formed thereon, which latter through the links s^2 , connecting the ends of the said arms with the link f , effect the moving into and out of alinement of the hinged toggle members, thereby causing the raising and lowering 45 of the carriage e .

The mechanism for actuating the toggle-joint is so arranged as to utilize to the very best advantage the power required to operate 50 the machine, as will be explained. It is apparent that in the straightening of the toggle the amount of power required increases as the hinged parts of the toggle approach alinement with each other. It is also apparent 55 that a given amount of power applied to the rock-shaft s will operate to the best advantage, just as the hinged ends of the links s^2 approach alinement with the center of the shaft s . Therefore in order that the power 60 applied to the shaft s may be used to the best advantage the said shaft is so located that the alinement of the hinged points of the toggle-joint and the alinement of the hinged ends of the links s^2 with the center of the 65 shafts are accomplished simultaneously. The arm p is located at such an angle on the shaft s relatively to the arms s' that the power ap-

plied thereto (through the link o) is utilized to the very best advantage to effect the rocking of the said shaft, the position of the said arm p being such that the centers of the pins m^2 and p' come into alinement with the center of the shaft h' simultaneously with the alinement of the centers of the hinged ends of the links s^2 and the shaft s and with the 75 alinement of the centers of the hinged parts of the toggle-joint.

The described arrangement of shafts h' and s and the toggle-joint, together with the several arms and links, enables the machine to 80 run much more smoothly than would otherwise be possible.

As already mentioned, the upper member or link g' of the toggle is extensible, such feature being provided in order that the distance between its table e^4 and the plate b^4 may be regulated by adjustment. To provide such adjustment of the toggle member, the lower portion g thereof is drilled and tapped to receive a screw g^2 , having a hand-wheel g^3 mounted thereon and also a non-threaded extension g^4 , that is received in the toggle portion g' . It will now be readily understood by reference to Fig. 3 that upon the rotation of the wheel g^3 the screw g^2 will be caused to 95 travel in the toggle portion g , thereby lengthening or shortening the link g g' .

The confronting ends of the lower toggle member f and of the portion g of the upper toggle are each recessed to receive between them a short bar t , and also at the points where the toggle members are hinged to the cross-frames e and d the said frames and adjacent ends of the toggle members are likewise recessed to receive similar short bars t . In order to hold the short bar t in position in the recesses of the cross-bars e and d , caps t' are employed, and in order to secure the toggle-links thereto and to each other, and to secure the short bar t between the adjacent ends of the toggle, ears t^2 are secured to the said toggle-links, in which ears the end portions of the bars t are secured. As seen in Fig. 4, these ears are inversely arranged, each being cut away at one end or side to allow 115 of its being engaged over the short shaft t . When the toggle is operated to raise or lower the carriage e , the links of the said toggle ride upon the pieces of short bar t , which are preferably of steel or phosphor-bronze and capable of resisting very great pressure. A 120 very strong hinge-joint is thus provided.

The driving-wheel k of the press is provided with a friction-clutch k' , that is engaged by an arm k^2 , mounted upon a shaft u , which latter is supported in suitable bearings on the frame a' . The shaft u also has mounted thereon an arm k^3 , whose outer end is connected by a spring k^4 with a suitable point on the frame a' , the said spring acting normally through the arms k^3 k^2 to hold the friction-clutch out of engagement with the wheel k . Secured to the outer end of the arm k^3 is a link v , connecting the said arm with a treadle

w, which latter is pivotally secured to the cross-frame *d* and is adapted to be operated to rock the shaft *u* (through the link *v* and arm *k*³) to cause the arm *k*² to carry the clutch *k* into engagement with the wheel *k* against the resisting force of the spring *k*⁴. In addition to the arms *k*² *k*³ the shaft *u* also carries an arm *y*, on the end of which there is located a roll *y*', adapted to engage a notched wheel *z*, mounted upon the shaft *h*'. In Fig. 1 and also in left-hand view of Fig. 6 the arm *y* is in such position that its roll *y*' lies in a notch *z*' of the wheel *z*, and when in such position the clutch *k*' is out of engagement with the wheel *k* and the machine is at rest. When it is desired to operate the machine, the treadle *w* is manipulated to rock the shaft *u*, so as to carry the clutch *k*' toward the wheel *k* and to cause the roll *y*' to travel outward in the notch *z*'. The just-described operation is continued until the clutch *k*' begins to lock itself to the wheel *k* to set the machine in motion. When the wheel *z* begins to rotate, a beveled side *z*² of the notch *z*' engages the roll *y*' to force the roll out of the said notch, as will be understood by reference to Fig. 6, thereby forcing the clutch *k*' into still closer engagement with the wheel *k*. After leaving the notch *z*' the roll *y*' rides upon the side of the wheel *z*, as shown in the right-hand view of Fig. 6, until another notch again comes coincident therewith, when the roll at once drops into said notch and the machine ceases to operate.

35 It will now be seen that the last-described mechanism provides a stop-motion whereby the operation of the machine is automatically controlled. Assuming that a machine constructed as 40 illustrated and described has been provided and that it is desired to use the same, the operation is substantially as follows: The material to be operated upon is placed on the lower or traveling plate or table *c*⁴, or rather 45 upon the bed-die mounted thereon. The clutch *k*' controlling the driving-wheel is then operated to set the machine in motion, which results in causing the said table to travel upward and carry the dies thereon into engagement with those of the stationary platen *b*⁴.

The material to be embossed (lying between the dies of the stationary and traveling plate) meanwhile receives the impress of the dies. The said dies are indicated in the drawings by dotted lines and are adapted to be heated, 55 as is common in this class of machinery; but as the said dies and the manner of heating them form no part of this invention it is thought unnecessary to illustrate or describe the same in detail.

60 My newly-invented machine as a whole is of simple construction, of comparatively light weight, is readily operated, and performs in a satisfactory manner the work for which it was designed.

Having thus described my invention, I claim—

1. In combination, a rectangular frame embodying a cross-head with fixed platen *b*⁴, a bed-plate slidably mounted on said frame, a 70 toggle as herein set forth for moving the said bed-plate, and means disposed substantially in vertical line with said platen, bed-plate and toggle for operating said toggle consisting of rock-shafts *s* and links *s*², and means for rock- 75 ing shaft *s* consisting of a crank *m*² and a rod *o* connecting said crank with the said rock-shaft.

2. The combination of the driving-shaft, the fixed platen and the movable bed-plate, 80 of toggle members connecting said bed-plate and a fixed portion of the frame for operating the bed-plate, a gear on said shaft, a shaft parallel with the driving-shaft, a gear thereon meshing with the gear on the driving-shaft 85 disposed in vertical alignment with said platen, bed-plate and toggle members, a crank-pin on the last-mentioned gear, a link connected thereto, a crank and crank-pin connected to the other end of said link, a rock- 90 shaft connected to said crank-pin and a connection between said rock-shaft and one of the toggle members, as set forth.

Signed at Mystic, Connecticut, this 7th day of October, 1901.

HAMILTON RICE.
